UNITED STATES PATENT OFFICE.

ALBA J. GILFILLAN, OF SMETHPORT, PENNSYLVANIA, AND WILLIAM H. WHITE, OF NYACK, NEW YORK.

DESIGN FOR A LUGGAGE-CARRIER FOR BICYCLES.

SPECIFICATION forming part of Design No. 28,295, dated February 15, 1898.

Application filed December 22, 1897. Serial No. 663,109. Term of patent 7 years.

To all whom it may concern:

Be it known that we, ALBA J. GILFILLAN, residing at Smethport, in the county of Mc-Kean and State of Pennsylvania, and WILLIAM H. WHITE, residing at Nyack, in the county of Rockland and State of New York, citizens of the United States, have invented and produced a new and original Design for a Luggage-Carrier for Bicycles, of which the following is a full, clear, and exact specification.

Reference is to be had to the accompanying drawings, forming a part of this specification, in which similar characters of reference indicate corresponding parts in all the views.

Figure 1 is a perspective view of a luggage-carrier for bicycles embodying our new design. Fig. 2 is a top plan view, and Fig. 3 is a side elevation thereof.

The design in its entirety consists of a central hollow body A, tapering arms B, extending forwardly therefrom in opposite directions, arms presenting compound curves, as seen in plan view, and merging into the body A and having at their outer ends a slight

gradual dip, as shown at F and as best seen in side view, Fig. 3, and at their extremities short vertically-extending members C appear. Openings E appear in said arms B near their junction with the body A. A depending boss 30 D extends from the center of the body A.

The leading features of the design consist of the hollow body, the tapering arms extending forwardly in opposite directions on curved lines from said body and having at 35 their outer ends short vertically-extending members.

We claim—

The design for a luggage-carrier for bicycles, herein shown and described.

ALBA J. GILFILLAN.
WILLIAM H. WHITE.
